UNITED STATES PATENT OFFICE.

ANDREW EKMAN, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

DOOR LATCH.

Application filed June 26, 1925. Serial No. 39,641.

To all whom it may concern:

Be it known that I, ANDREW EKMAN, a subject of the King of Sweden, residing at Grand Rapids, in the county of Kent and 5 State of Michigan, have invented new and useful Improvements in Door Latches, of which the following is a specification.

The present invention relates to door latches; and its object is to provide such a 10 latch which shall be very simple in construction, comprising few parts which may be readily assembled; and further, to provide such a latch having a latching bolt rockable in either direction into and out of latching 15 engagement with its keeper; and further, to provide such a latch having improved means for causing the latching bolt to automatically engage its keeper when the door is shut.

20 These and any other objects hereinafter appearing are attained by, and the invention finds preferable embodiment in, the door latch hereinafter particularly described in the body of this specification and illustrated 25 by the accompanying drawings, in which:—

Figure 1 is a face view of a door latch;

Figure 2 is a right-hand side view thereof;

Figure 3 is a left-hand side view of the same;

30 Figure 4 is a left-hand side view thereof and of the latch's keeper;

Figure 5 is a front view of the latch and keeper, a portion of the casing being broken away;

35 Figure 6 is a sectional view of the latch and casing taken on line 6—6 of Figures 5 and 7;

Figure 7 is a sectional view of the same taken on line 7—7 of Figures 5 and 6;

40 Figure 8 is a face view of a modified construction of the keeper; and

Figure 9 is a side view thereof.

In the embodiment of the invention chosen for illustration by the drawings and 45 for detailed description in the body of this specification, the door latch is shown mounted adjacent the left-hand free edge of a swinging door 1, the latch's keeper 2 being mounted on the door's jamb or casing 3.

50 The latch has a casing 4 through holes 5 in which screws 20 extend for mounting the latch. Inside this casing a latching bolt 6 is mounted to rock vertically into and out of operative position in which its outer end 7 latchingly engages the keeper. This bolt 6

has members 8, 9, spaced apart in the bolt's transverse direction, which members rock and slide in bearings 10, 11 respectively in the right-hand wall of the casing, through which the ends 12, 13 of these members extend, whereby the bolt is held in position in the casing. It will be seen that when the handle portion 14 of the bolt is moved downwardly to disengage the end 7 from the keeper, the upper member 8 rocks on its bearing 10 while the lower member 9 slides in its bearing 11; and that, if the latch is applied adjacent the right-hand free edge of a door, so that the ends of the casing are now reversed in position, the downward movement of said handle portion to disengage the bolt from the keeper causes the member 9 to rock on its bearing 11 while the member 8 slides in its bearing 10. It will thus be seen that this latch may be applied adjacent 75 either the right-hand edge or the left-hand edge of a swinging door. Or, as indicated in Figures 8 and 9, the keeper 2¹ may receive the outer end of the bolt either from above or from below; in which case, either member 8 or 9 may rock on its bearing and the other member slide in its bearing in the disengaging movement of the bolt from the keeper.

The wall 16 of the casing has a bearing orifice 17 opposite the pair of spaced bearing orifices 10, 11, the end 7 of the bolt projecting through the orifice 17. A pair of vertically spaced apart supports or shoulders 18, 19 are formed in the bearing orifice 17, and are adapted to receive the bolt in resting position thereon when the same is rocked in either direction to keeper-disengaging position. When the door is shut, the bolt being held in such position, the end 7 of the bolt strikes the keeper or the door jamb and is pushed from the support or shoulder on which it rests and thereupon falls into latching engagement with the keeper.

A wire spring 21 is seated in the casing, its ends passing around the screws 20, 20 100 and its middle portion 22 extending from the front wall of the casing and pressing on the side of the bolt adjacent said wall. On either side of the main portion of the bolt the spring also presses at 23, 24 on the members 8, 9. The action of this spring thus presses the bolt into its operative position in which its end 7 latchingly engages the keeper, and presses said end 7 into resting position on the support 18 or 19; and also 110

presses the members 8, 9 in their rocking contact or engagement with their bearings 10, 11. This spring thus serves to hold the parts in place.

5 It will be seen that this latch is of very simple construction, comprising only three parts—the casing, the latching bolt and the said spring; and that these parts may be readily assembled.

10 The invention being intended to be pointed out in the claims, is not to be limited to or by details of construction of the particular embodiment thereof illustrated by the drawings or hereinbefore described.

15 I claim:

1. In a door latch: a keeper; a bolt having an operating handle portion and movable out of latching engagement therewith rockingly about either of a pair of axes spaced 20 in the bolt's transverse direction.

2. In a door latch: a keeper; a bolt spring-pressed into latching engagement therewith and having an operating handle portion and movable out of said engagement rockingly 25 about either of a pair of axes spaced in the bolt's transverse direction.

3. In a door latch: a keeper; a pair of spaced bearings, a bolt having a pair of members spaced in the bolt's transverse direction and movable rockingly and slidably in said bearings respectively in the bolt's disengaging movements from the keeper.

4. In a door latch: a keeper; a pair of spaced bearings; a bolt spring-pressed into latching engagement with the keeper and having a pair of members spaced in the bolt's transverse direction and movable rockingly and slidably in said bearings respectively in the bolt's disengaging movements 40 from the keeper.

5. In a door latch: a keeper; a pair of spaced bearings; a bolt having a pair of members spaced in the bolt's transverse direction, one of said members being movable 45 slidably and the other of said members being movable rockingly in said bearings respectively in the bolt's disengaging movement from the keeper.

6. In a door latch: a keeper; a pair of spaced bearings; a bolt spring-pressed into latching engagement with the keeper and having a pair of members spaced in the bolt's transverse direction, one of said members being movable slidably and the other 55 of said members being movable rockingly in said bearings respectively in the bolt's disengaging movement from the keeper.

7. In a door latch: a keeper; a pair of

spaced bearings; a bolt having a pair of members spaced in the bolt's transverse direction, one of said members being movable slidably and the other of said members being movable rockingly in said bearings respectively in the bolt's disengaging movement from the keeper; a spring pressing the bolt into latching engagement with the keeper and pressing the second-mentioned of said members into engagement with the bearing on which it rocks.

8. In a door latch: a keeper; a casing 70 having adjacent the keeper a bearing and having a pair of spaced bearings disposed oppositely to the first-mentioned bearing; a rockable bolt extending through the first-mentioned bearing and having a pair of 75 members spaced in the bolt's transverse direction and extending through said pair of bearings respectively, one of said members being movable slidably and the other of said members being movable rockingly in 80 said pair of bearings respectively in the bolt's disengaging movement from the keeper; a spring pressing the bolt into latching engagement with the keeper and pressing the second-mentioned of said members 85 into engagement with the bearing on which it rocks.

9. In a door latch: a keeper; a support; a pair of spaced bearings; a bolt having a pair of members spaced in the bolt's transverse direction, one of said members being movable slidably and the other of said members being movable rockingly in said bearings respectively in the bolt's disengaging movement from the keeper; a spring pressing the bolt into latching engagement with the keeper and into resting position on the support and pressing the second-mentioned 90 of said members into engagement with the bearing on which it rocks.

10. In a door latch: a keeper; a pair of supports; a pair of spaced bearings; a bolt having a pair of members spaced in the bolt's transverse direction and movable rockingly and slidably in said bearings respectively 95 in the bolt's disengaging movements from the keeper; a spring pressing the bolt into latching engagement with the keeper and into resting position on either of the supports and pressing said members into engagement 100 with the bearings on which they respectively rock.

In testimony whereof I have hereunto set my hand at Grand Rapids, Michigan, this 22nd day of June, 1925.

ANDREW EKMAN.
